(57) **CLAIM**

We claim the ornamental design for a footwear upper portion, as shown and described.

DESCRIPTION

FIG. 1 is a perspective view of a footwear upper portion, seen from the front and right side thereof, showing our new design;

FIG. 2 is a right side view thereof; and,

FIG. 3 is a left side view thereof.

The zig-zag pattern on the right and left sides of the design represents an embossed pattern.

The broken lines extending diagonally upwardly and forwardly from the heel area of the design represent stitching. The phantom line showing in the figures of the sole and other parts of the footwear upper is for illustrative purposes only and forms no part of the claimed design.
